(57) **CLAIM**

The ornamental design for a calibrator case, as shown and described.

DESCRIPTION

FIG. 1 is a front perspective view of a calibrator case.

FIG. 2 is a back perspective view thereof.

FIG. 3 is a front plan view thereof.

FIG. 4 is a back plan view thereof.

FIG. 5 is a left view thereof.

FIG. 6 is a right view thereof.

FIG. 7 is a bottom view thereof.

FIG. 8 is a top view thereof.

FIG. 9 is a front perspective view of a second embodiment of a calibrator case.

FIG. 10 is a back perspective view thereof.

FIG. 11 is a front plan view thereof.

FIG. 12 is a back plan view thereof.

FIG. 13 is a left view thereof.

FIG. 14 is a right view thereof.

FIG. 15 is a bottom view thereof.

FIG. 16 is a top view thereof.

FIG. 17 is a front perspective view of a third embodiment of a calibrator case.

FIG. 18 is a back perspective view thereof.

FIG. 19 is a front plan view thereof.

FIG. 20 is a back plan view thereof.

FIG. 21 is a left view thereof.

FIG. 22 is a right view thereof.

FIG. 23 is a bottom view thereof.

FIG. 24 is a top view thereof.

FIG. 25 is a front perspective view of a fourth embodiment of a calibrator case.

FIG. 26 is a back perspective view thereof.

FIG. 27 is a front plan view thereof.

FIG. 28 is a back plan view thereof.

FIG. 29 is a left view thereof.

FIG. 30 is a right view thereof.

FIG. 31 is a bottom view thereof; and,

FIG. 32 is a top view thereof.

The broken lines form no part of the claimed design.

1 Claim, 24 Drawing Sheets
